Primary Examiner — April Rivas(74) *Attorney, Agent, or Firm* — Lee, Hong, Degerman, Kang & Waimey(57) **CLAIM**

The ornamental design for an octagon-shaped luggage, as shown and described.

DESCRIPTION

FIG. 1 is a front perspective view of a luggage;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a front perspective view of a luggage;

FIG. 9 is a front view thereof;

FIG. 10 is a rear view thereof;

FIG. 11 is a first side view thereof;

FIG. 12 is a second side view thereof;

FIG. 13 is a top view thereof; and,

FIG. 14 is a bottom view thereof.

The broken lines illustrate portions of the octagon-shaped luggage and form no part of the claimed design.
